UNITED STATES PATENT OFFICE

ARTHUR W. DAVISON, OF JAMESTOWN, NEW YORK

DESIGN FOR AN EDIBLE RECEPTACLE

Application filed October 24, 1932. Serial No. 45,532. Term of patent 14 years.

To all whom it may concern:

Be it known that I, ARTHUR W. DAVISON, a citizen of the United States, residing at Jamestown, in the county of Chautauqua and State of New York, have invented a new, original, and ornamental Design for an Edible Receptacle, of which the following is a specification, reference being had to the accompanying drawing, forming part thereof, and in which—

Figure 1 is a side elevation of my design for edible receptacle;

Figure 2 is an end view of the receptacle shown in Figure 1;

Figure 3 is a top plan view of the receptacle; and

Figure 4 is a bottom plan view of the receptacle.

I claim:

The ornamental design for an edible receptacle substantially as shown.

ARTHUR W. DAVISON,
